BRASSIERE

Nettie Blum, Oceanside, N. Y.

Application February 19, 1942, Serial No. 431,552

5 Claims. (Cl. 2—42)

This invention relates to brassières and the object of the invention is to provide a pocket construction for brassières comprising a lower half cup pocket portion including a central integral top segment portion coupled with the upper edge of the pocket in such manner as to form a curved, concaved portion of the segment and adjacent area of the pocket to fit the nipple and adjacent area of the breast while leaving the major portion of the top of the breast exposed, and with these and other objects in view, the invention consists in a garment of the class described which is constructed as more fully hereinafter set forth. The novel features of the invention will be best understood from the following description when taken together with the accompanying drawing, in which certain embodiments of the invention are disclosed, and in which the separate parts are designated by suitable reference characters in each of the views, and in which:

Fig. 1 is a front view diagrammatically illustrating one form of garment made according to my invention.

Fig. 2 is a partial section on the line 2—2 of Fig. 1.

Fig. 3 is a detailed view of a blank employed in forming a pocket illustrating another adaptation of the invention.

Fig. 4 is a view similar to Fig. 1 showing only a part of the construction and showing a modification; and

Fig. 5 is a view similar to Fig. 4 showing another adaptation of the invention.

My present invention deals with a brassière of the general type and kind disclosed in my Patent #2,267,365 and deals more specifically with the method of constructing the pockets of the brassière as well as methods or means for mounting or supporting the pockets.

In order to produce a more comfortable and better fitting pocket and one which will eliminate irritation to the nipple portion of the breast, I have constructed the pocket or at least the central portion thereof from a single section of material which may be of one or more ply thickness and so cutting this particular section, as to form at the upper edge thereof a concaved, curved segment in conjunction with the curvature of the pocket proper to conform snugly and yet comfortably on the nipple section of the breast and eliminate seams at said section.

In Fig. 1 of the drawing, is illustrated one form of brassière and pocket construction wherein each pocket 10 is made from a single section

or blank, of single or multiple ply material. In some instances, this material is faced on its inner and outer surfaces and may be composed of rubberized fabric or an elastic fabric. The lower portion 11 of each pocket forms what might be termed a half-cup for supporting the lower portion of the breast. Joining the central top edge portion of the cup is a segment forming part 12, cut to form V-notches at the sides thereof as indicated in dotted lines at 13 at the right of Fig. 1 of the drawing. The edges 14 formed by the notches are secured to the upper edges 15 to form the segments 12 and adjacent portions of the pockets 11, curved concaved nipple receiving portions 16, note Fig. 2 of the drawing. In forming the pockets and integral segments from sheet rubber, the attachment or coupling of the edges 14, 15 may be accomplished by cementing or vulcanizing and when other materials are employed, the parts may be stitched together. It will also be understood that in more expensive garments, a rubber brassière pocket may be molded in the contour generally produced by the assemblage of the parts as herein specifically defined. When rubber is employed, it is desirable to face the inner surface thereof with a soft fabric to eliminate the undesirable contact of rubber directly with the body and in some instances this facing may be in the form of a padding.

Pockets of the specific type and kind disclosed in Fig. 1 as well as later described in connection with Fig. 4, may be mounted upon the body of the wearer in accordance with the specific teachings in the patent hereinbefore referred to, or as taught in co-pending applications Serial Numbers 431,110, February 16, 1942 and 431,919, February 23, 1942. In Fig. 1 of the drawing, one method of mounting the pockets is disclosed.

The adjacent edges of the pockets are joined by crossed straps 17 and 18 and these straps may be composed of elastic or partially of elastic material. A body encircling strap 19 is attached to the lower outer side portions of the pockets 10 and has means at 20 to adjust the strap and the strap may also include elastic portions 21. At 22 are shown shoulder straps coupled with the strap 19 and with the upper outer corners of the pockets 10. The straps 22 are provided with buckles 23 to adjust the same upon the body of the wearer.

In Fig. 3 of the drawing, I have shown a slight modification of the construction shown in Fig. 1 where a single pocket 24 is disclosed the pocket being constructed in the same manner as the

5 pocket 10, that is to say, will include the semi-cup portions 25 and integral upper edge segments 26. The pockets are adapted for mounting individually in any type or kind of garment to be supported by the garment upon the body of the wearer. For example, the pockets may be built into an evening gown, particularly where all types and kinds of shoulder straps are to be dispensed with or to be built into such garments as bathing suits. For this purpose the inner edge portion of each pocket will have a strap 27 for supporting said edge upon the garment, the outer edge will have upper and lower straps 28 and 29, and the lower edge will have a depending strap 30. All of the straps 27-30 may be composed entirely, or in part of elastic material and may be simply stitched into the garment, or suitable fastenings may be provided for detachably coupling the same with the garment, and any of the conventional types and kinds of fastening devices can be used for this purpose and for this reason they are not shown as they form no specific part of the present invention.

10 In the use of individual pockets, such as the pocket 24, and in construction of the rigid or semi-rigid materials, it will be apparent that these pockets build into the garment a breast supporting structure which will support the breasts in raised position either through the medium of the tight fitting of the garment, or through other supporting means which may be provided on the garment.

15 In Fig. 4 of the drawing is shown another method of constructing each of the pockets of a brassière by providing a central body portion 31 including at its upper edge the integral segment 32 and in utilizing inner side sections 33 and outer side sections 34 of a different type and kind of material, as for example, as a padded or quilted fabric to give body and semi-rigidity to the sections as will be apparent. The section 33 has the stitchings 35 thereof extending more or less vertically, whereas the section 34 has its stitchings 36 extending more or less horizontally. I have also found that the inner portions of the pockets require greater rigidity than the outer side portions thereof, particularly in a garment which is hung from the sides only of the brassière as is shown in Fig. 1 and for this reason the stitchings 35 are arranged vertically, whereas the outer sections 34 have the horizontal arrangement of stitchings 36. It will, of course, be apparent that the illustrations in the accompanying drawing are diagrammatic in the sense of eliminating the detailed stitchings employed in securing the several parts together and all matters of trim and ornamentation of the garments have been eliminated in order to simplify the illustration. Aside from the method of constructing each pocket, the structure of Fig. 4 is the same as that of Fig. 1 and is also applicable to the structure of Fig. 1.

20 In Fig. 5 of the drawing, I have shown at 37 a single pocket of a brassière which may be constructed in accordance with the teachings in either Fig. 1 or Fig. 4. The modifications of Fig. 5 reside primarily in the use of a detachable strap 38 detachably coupled with the inner edge of the pocket as seen at 39 and also detachably and adjustably coupled to the shoulder strap 40, as indicated at 41. One of the straps 38 will be used at each side of the garment and by making these straps entirely detachable the garment is adaptable for use with dresses having wide, low cut necks, as well as dresses of the V-

25 neck type. In other words, the garment may be worn with the straps 38 as a unit part thereof and the wearer may couple and uncouple the straps in different uses of the garment. In Fig. 5 the strap 38 is shown coupled with the inner edge of an opposed pocket. It will be apparent, however, that in some instances the strap 38 may couple with the inner end of the pocket to which the shoulder strap 40 is attached.

30 In all forms of the garment, the lower edge portions of the pockets are made to flex onto the body of the wearer beneath the breast as indicated at 42 in Fig. 2 of the drawing and in the molding of the pockets as described, it is preferred that this curvature of the lower edge be directly molded in the garment and this especially desirable when the pockets are shaped from semi-rigid or elastic materials. In some instances, sheets or materials including sheet metal could also be die-formed to the desired contour. However, in such instances the garments will have to be made into sizes suiting the varying breast sizes in different body sizes. From this standpoint, the yieldable or resilient semi-rigid materials are preferred or the use of bias cut fabrics with reinforcements therein.

35 Having fully described my invention, what I claim as new and desire to secure by Letters Patent is:

30 1. A brassière of the class described comprising two substantially similar breast receiving and supporting members, each of said members comprising a half pocket disposed on the lower portion and sides of the breast, the upper edge of each member having a narrow integral part extending along the upper edge of the member and forming a concaved segment overlying the nipple and adjacent area of the breast, leaving the major part of the upper portion of the breast exposed, the central portion only of said part being integrally united with said member, means joining the adjacent ends of said members, and means comprising back and shoulder straps attached to outer side edges only of said members for supporting said members upon the body of the wearer.

35 2. A brassière of the class described comprising two substantially similar breast receiving and supporting members, each of said members comprising a half pocket disposed on the lower portion and sides of the breast, the upper edge of each member having a narrow integral part extending along the upper edge of the member and forming a concaved segment overlying the nipple and adjacent area of the breast, leaving the major part of the upper portion of the breast exposed, the central portion only of said part being integrally united with said member, means joining the adjacent ends of said members, means comprising back and shoulder straps attached to outer side edges only of said members for supporting said members upon the body of the wearer, and other straps detachable from the shoulder straps and the inner end of an opposed member forming additional supports of said members upon the body of the wearer.

40 3. A brassiere of the class described comprising two substantially similar breast receiving and supporting members, each of said members comprising a half pocket disposed on the lower portion and sides of the breast, the upper edge of each member having a narrow integral part extending along the upper edge of the member and forming a concaved segment overlying the

nipple and adjacent area of the breast, leaving the major part of the upper portion of the breast exposed, the central portion only of said part being integrally united with said member, means joining the adjacent ends of said members, means comprising back and shoulder straps attached to outer side edges only of said members for supporting said members upon the body of the wearer, other straps detachable from the shoulder straps and the inner end of an opposed member forming additional supports of said members upon the body of the wearer, and the attachment of said last named straps with the shoulder straps being adjustable.

4. A brassière of the class described comprising two substantially similar breast receiving and supporting members, each of said members comprising a half pocket disposed on the lower portions and sides of the breasts, each member having centrally of the upper edge thereof an integral projecting part, said part joining the member in a portion shorter than the full length of said part to form projecting ends on said part, said projecting ends being secured to the upper edge of said member beyond said shorter portion in forming at the upper edge of said member a concaved segment overlying the nipple and adjacent area of the breast, leaving the major part of the upper portion of the breasts exposed, means joining adjacent ends of said members, 30

and means comprising back and shoulder straps attached to outer side edges only of said members for supporting said members upon the body of the wearer.

5. A brassière of the class described comprising two substantially similar breast receiving and supporting members, each of said members comprising a half pocket disposed on the lower portions and sides of the breasts, each member having centrally of the upper edge thereof an integral projecting part, said part joining the member in a portion shorter than the full length of said part to form projecting ends on said part, said projecting ends being secured to the upper edge of said member beyond said shorter portion in forming at the upper edge of said member a concaved segment overlying the nipple and adjacent area of the breasts, leaving the major part of the upper portion of the breasts exposed, 10 means joining adjacent ends of said members, means comprising back and shoulder straps attached to outer side edges only of said members for supporting said members upon the body wearer, the central portion of each supporting member including the segment thereof being composed of sheet rubber, and each member at opposite sides of the central portion comprising reinforced fabric.
